UNITED STATES PATENT OFFICE

WADE H. REICHARD, OF ROCHESTER, NEW YORK, ASSIGNOR TO GENERAL RAILWAY SIGNAL COMPANY, OF ROCHESTER, NEW YORK

CONTINUOUS INDUCTIVE TRAIN-CONTROL SYSTEM

Application filed January 30, 1929. Serial No. 336,090.

This invention relates to train control systems of the continuous inductive permissive type, in which an acknowledgment is required at each of successive stop signals, and relates more particularly to the car-carried apparatus thereof. 55

In accordance with the present invention suitable brake control apparatus, in the first instance governed in accordance with current 10 flowing in the track rails and held inactive in clear territory, is held inactive in non-clear territory by suitable car-carried means requiring manual acknowledgment, which means is again rendered inactive at the end 15 of each block of the railway system in response to energy flowing in a track loop at the end of such block. Suitable acknowledging means is provided to render the brake control means inactive when the train is travelling in non-clear territory, and suitable 20 reset means is employed for restoring the brake control means in the event it is automatically actuated. The invention has been exemplified in three different forms, in the 25 first of which both the acknowledging and the reset means are of the pneumatic type, in the second form of which both the reset and the acknowledging means are of the electrically operated type, and in the third 30 form the acknowledging means is of the electric type and the reset means is of the pneumatic type. These three forms of the invention will be briefly described after 35 which the novel features thereof will be pointed out in claims. 85

In describing the invention reference will be made to the accompanying drawings in which:—

Fig. 1 illustrates both trackway and car-carried apparatus embodying one form of the invention; 40

Fig. 2 shows the car-carried apparatus of a modified form of the invention; and

Fig. 3 shows still another modified form 45 of the invention.

Referring to Fig. 1 of the drawings the track comprising rails 1 is divided into blocks by insulating joints 2, of which the block I and the adjacent ends of blocks H 50 and K only have been shown. Since the

various blocks are the same it is sufficient to describe only the apparatus of one block, the corresponding devices of other blocks being designated by like reference characters having distinctive exponents. 55

At the entrance end of each block is provided the usual wayside signal Z, controlled in accordance with traffic conditions in advance, in any suitable manner not specifically shown. Each block is also provided with the usual track circuit comprising, a track relay T and a track battery 4; this track battery 4 has the secondary winding of a transformer 5 connected in series therewith, this transformer superimposing an alternating train control current on the track circuit direct current for reasons more clearly pointed out hereinafter. It should be noted that the circuit of the primary winding of the transformer 5 at the exit end of a particular block is open at the front contacts 6 of the track relay T, when the next block in advance is occupied. This in order to manifest on a train in a particular block the occupancy of the block next in advance. 75 Also, for a short distance at the exit end of each block is provided a loop having its wires disposed adjacent the track rails so as to simulate the flow of current in such track rails when current is flowing in the loop. This 80 loop is constantly energized from a transformer 7. The transformers 5 and 7 receive their energy from a transmission line TL supplied with energy from an alternating current generator AC. 85

On each train is contained a main control relay CR of any suitable type, but preferably of the polyphase inductive type, having windings 10 and 11, which are energized respectively by the coils of track elements 12 and 13, the current of which is amplified by a suitable amplifier A. The electrical constants of the circuits and the amplifier A described are such that current flowing down one track rail and back 90 through the other produces currents displaced in phase and flowing in coils 10 and 11 of relay CR, so as to cause the contacts of the control relay CR to assume the right hand normal position, as shown in the drawings. 95

For a more detailed description of this phase of applicant's invention attention is directed to the patent to W. W. Wenzel No. 1,692,361 dated November 20, 1928. With no current flowing in the track rails the contacts of the control relay CR assume the pendent position, and with currents flowing in the same direction in the two track rails the control relay CR assumes the reversed dotted position. From these considerations, it is noted that with the train travelling in a clear block the control relay CR assumes its right hand energized position, with a train travelling in a caution or danger block the control relay CR assumes its deenergized position, and with stray alternating current flowing in the same direction in the two track rails the control relay CR is caused to assume its reversed dotted position.

It is apparent from the drawings that the green lamp is energized under clear traffic conditions, and the red lamp R is energized under caution and danger traffic conditions through the contact 15 of the relay CR.

The car-carried apparatus also includes the usual air brake mechanism (not shown), two electro-pneumatic valves EPV¹ and EPV², a reset valve having a handle 20, an acknowledging valve having a handle 21, a check valve 22, an air switch AS and a reset reservoir 23. Under normal clear traffic conditions the electro-pneumatic valve EPV¹ is energized through the following circuit:—beginning at the terminal B of a suitable battery, wire 26, contact 27 of relay CR, wire 28, winding of the device EPV¹, to common return wire C connected to the other terminal of said battery. It is believed that the apparatus can be best explained by considering the operation of the system.

Fig. 1 operation.—With the apparatus of Fig. 1 in its normal condition, as shown, fluid pressure may flow from a suitable main reservoir MR (not specifically shown) through pipe 30, acknowledging valve 31 having a handle 21, pipe 32, valve 18 opening into a chamber of the electro-pneumatic valve EPV¹, pipe 33, check valve 22, pipes 34 and 35, to the sylphon or expandable chamber 36 of the pneumatic relay PR. Incidentally, pressure fluid may also flow through the pipe 37 and reset valve 38 to the reset reservoir 23. With the sylphon chamber 36 expanded the valve 40 of pneumatic relay PR is seated and the valve 41 is unseated, thus permitting pressure fluid to flow from the main reservoir through pipe 42, chamber of the pneumatic relay PR, pipes 43 and 44 to suitable brake control apparatus which maintains the brakes inactive, but which upon venting of pressure from the pipe 44 causes said brake control apparatus to effect a brake application. Incidentally, with pressure applied to the pipe 44 the sylphon 45 of the

air switch AS is expanded thus causing closure of contacts 46.

If now the train enters the block I with the block K in advance thereof occupied by another train, no alternating current is detected on the rear train and the control relay CR assumes its de-energized conditions. De-energization of the control relay CR breaks the energizing circuit for the device EPV¹ and completes the energizing circuit for the device EPV², the circuit for the latter of which may be traced as follows:—beginning at the terminal B, contact 15 of the control relay CR assuming its de-energized position, wires 50 and 51, winding of the device EPV², wire 52, contacts 46 to common return wire C connected to the other side of the source containing terminal B. With the device EPV² assuming its energized condition fluid pressure may flow from the main reservoir MR through pipe 54, valve 48 in chamber of the valve EPV², pipes 55 and 56 to the chamber 60 having a stick valve 57 therein, to atmosphere. The piston 57¹ in the chamber 60 is loose fitting so that the air may leak through between it and the chamber 60, and pressure cannot be built up in pipe 56 unless first this piston 57¹ is manually placed on the valve seat 57, after which no air can escape and the trapped air will hold the piston 57¹ down and will expand the sylphon chamber 59, thus making 57 a valve that will stick closed.

If the engineer is alert, as he should be in response to the sounding of the whistle W on the electro-pneumatic valve EPV¹, which is sounded due to air exhausted from the chambers 23 and 36, when this valve is de-energized, he will depress the handle 21 of the acknowledging valve 31 and will thereby close the stick valve 57 which will remain closed in response to pressure built up in pipes 55 and 56, and will cause this pressure to flow through pipe 58 to the sylphon chamber 59, thereby returning the valves in the electro-pneumatic valve EPV¹ to normal. The engineer is, of course, required to return the handle 21 to its normal position in order to allow main reservoir pressure to flow through the valve 31, pipes 32, 33, 34, and 35 to the pneumatic relay PR. In so doing the stick valve 57 remains closed by the built-up pressure. It is thus seen that the acknowledging handle 21 is protected against misuse and cannot be tied down, since it must be returned to its normal position for reasons just mentioned, the stick valve 57 remaining closed against the pressure of spring 58 by reason of the pressure existing in pipe 56. The train may thus travel through the caution block I without the presence of alternating current flowing in the track rails.

When the train in question reaches the end of the block I, having moved in the normal direction of traffic as indicated by the arrow,

the relay CR is caused to assume its normal position as soon as the car elements 12 and 13 intercept loop 8¹. This energization of the control relay CR reapplys current to the winding of the device EPV¹ and de-energizes the winding of the device EPV². With the device EPV² de-energized pressure is exhausted to atmosphere from the pipes 55 and 56 through port of valve 49 and the exhaust port to atmosphere from EPV², thereby causing the stick valve 57 to return to its normal position as shown in the drawings, or in other words all of the car-carried apparatus is restored to its normal condition. As soon as the train passes off of the loop 8¹, the engineer is again required to manifest his vigilance by depressing the handle 21, and in a manner as already described may supply pressure to the sylphon chamber 36 through the device EPV¹, held in its normal position pneumatically by pressure existing in the sylphon chamber 59. It is of course understood that the control relay CR cannot receive energy from the track upon its entrance into block K, because this block is occupied by another train ahead which other train shunts the alternating current, from one rail to the other and prevents it from reaching the rear train. Should the engineer have failed to manifest his vigilance and thereby not have closed the stick valve 57 by depression of the handle 21, his failure to act preventing pressure building up in the sylphon chamber 59, the electro-pneumatic valve EPV¹ would have assumed its de-energized position thereby permitting the pressure in sylphon chamber 36 to escape through the leakage port 24 in check valve 22 and through the whistle W, sounding the same. It is to be understood that the acknowledging handle 21 when depressed will seat the loose fitting piston 57¹ in chamber 60 on seat 57, thus closing the valve 57—57¹, which will then stick closed by trapped air pressure. This failure to act would have caused the pneumatic relay PR to have been actuated after a predetermined time depending upon the size of the leakage port 24. Such actuation of the pneumatic relay PR would of course effect a brake application by venting pipe 44, and would effect opening of contacts 46, thereby preventing energization or effecting de-energization, as the case may be, of the electro-pneumatic valve EPV². With the contacts 46 once opened, it is no longer possible to energize the device EPV² and it leaves the engineer helpless to prevent a brake application and the train will be brought to a stop. When the train has been brought to a stop the engineer may alight to the ground and operate the reset handle 20 to its dotted position, thereby charging the reset reservoir 23 to main reservoir pressure as is obvious from the drawings. If the engineer then returns the rest handle 20 to

its normal position the pressure stored in chamber 23 flows to the sylphon chamber 36, and thereby restores the pneumatic relay PR to normal, and in turn causes restoration of the air switch AS, which in turn applies current to the electro-pneumatic valve EPV². The engineer may then depress the handle 21 of the acknowledging device and cause pressure to be built up in the sylphon chamber 59, and effect restoration of the valve EPV¹. It is thus noted that the reset valve 38 is protected against misuse in that it must be returned to its normal position to connect the reset reservoir 23 to the sylphon chamber 36, and if this had not been done when the next change to non-clear conditions occurs the time of venting out chamber 36 through the restricted port 24 would be reduced to such an extent that the brakes would be applied even though the engineer were to perform his acknowledging act. Further the engineer is penalized for allowing a brake application by reason of the fact that he must alight to the ground to effect resetting of the apparatus to normal.

Fig. 2 operation.—In view of the detailed description of the various devices of the car-carried apparatus shown in Fig. 1, and the manner in which the control relay CR is controlled in accordance with traffic conditions and the manner in which energy is transmitted from loop circuits at the end of blocks, and also by reason of the similarity of the apparatus used, it is deemed sufficient to describe only the operation of the modified form of the invention shown in Fig. 2 of the drawings. It may be stated that the results accomplished by the arrangement shown in Fig. 2 are substantially the same as that of Fig. 1, the principal distinction being that the acknowledgment and reset functions are accomplished electrically instead of pneumatically. For this reason, an acknowledging push button 65 and a reset push button 66 have been provided.

Under normal clear traffic conditions the green lamp G is illuminated by a circuit readily traced in the drawings and including a contact 15 of the control relay CR. Likewise the electro-pneumatic valve EPV¹ which is constructed as the corresponding device in Fig. 1 except that the sylphon chamber 59 is omitted, is energized through the following circuit:—beginning at the terminal B, wire 26, contact 27 of the control relay CR in its normal right-hand position, wire 68, contact 69 of the reset push button 66, wire 70, contact 71 of the acknowledging push button 65, wire 72, winding of the electro-pneumatic valve EPV¹ to common return wire C. With this circuit completed the device EPV¹ is energized to seat its valve 19 and to unseat its valve 18, thereby permitting fluid pressure to flow from main reservoir MR, pipe 32, chamber of de-

vice EPV¹, pipe 33, ball 25 of the check valve 22, pipe 34, to capacity tank 23 and sylphon chamber 36. With pressure in the sylphon chamber 36 the brakes are maintained released for reasons as heretofore described.

If now the train in question enters caution territory, and the relay CR assumes its de-energized condition, for reasons already given, the device EPV¹ is de-energized and pressure fluid which may flow from the chambers 23 and 36 escapes through the restricted opening 24 in check valve 22 through the valve chamber and whistle W to atmosphere, thus sounding the whistle W to inform the engineer that he must perform an acknowledging act to prevent an automatic brake application. If the engineer is alert and immediately acts and depresses the acknowledging push button 65 he may avail himself of the use of the acknowledging relay by completing the following pick-up circuit for this relay AR:—beginning at the terminal B of a suitable source of current, wire 74, contact 16 of the control relay CR in its pendant position, wires 75 and 76, push button contact 77 of the acknowledging push button 65, wires 78 and 79, winding of the acknowledging relay AR, through wires 80 and 81 to common return wire C. With the acknowledging relay AR once energized it is maintained energized through its stick circuit including its own front contact 82 and contact 16 of the control relay CR, which circuit may be readily traced in the drawings. It is, of course, understood that if the engineer is not alert to the extent of allowing contacts 46 of AS to open before he depresses the push button 65 to pick up the relay AR, this operation will avail him nothing, this because closure of contact 86 of relay AR cannot close the auxiliary circuit for the device EPV¹ with the contacts 46 open.

The engineer may now allow the return of push button 65 to its normal position by the action of a suitable spring (not shown), in which event the following circuit for the device EPV¹ is completed:—beginning at the terminal B, wire 84, contact 46 of the air switch AS, wire 85, front contact 86 of the acknowledging relay AR, wire 87, contact 71 of the acknowledging push button 65, wire 72, winding of the device EPV¹, to common return wire C. The train may thus proceed through the caution block even though there is no current flowing in the track rails, and by reason whereof the control relay CR is in its de-energized condition. In this connection it should be understood that the size of the leakage port 24 in check valve 22 and the volume of the capacity tank 23 are such, that the time required for fluid pressure to escape from sylphon chamber 36 to an extent to allow spring 39 to open valve 40 and close valve 41 is sufficient to permit the engineer

to acknowledge and reapply current through the device EPV¹. Also, it should be noted that the acknowledging push button 65 is protected against misuse such as tying down, in that the device EPV¹ cannot be energized so long as the push button 65 is maintained depressed, this by reason of the normally closed contact 71 thereof. Although this contact 71 may be constructed to open only after a period of time following depression of push button 65, it may if desired be connected directly to the push button and open immediately.

Should the engineer have failed to manifest his vigilance, that is, should he have depressed the acknowledging push button 65 too late, the pneumatic relay PR would have vented the pipe 44 to effect a brake application, and such venting would have caused the air switch AS to open its contact 46, thereby preventing the engineer by reason of his delay in acknowledgment from completing the auxiliary circuit for the device EPV¹ heretofore traced and including contact 46. Under these conditions the train is of course brought to a stop by an automatic brake application, and the engineer must either wait until traffic conditions in advance clear up and the control relay CR is re-energized, or he must alight to the ground and operate his reset push button 66, in which event the following circuit for the device EPV¹ is completed:—beginning at the terminal B, wire 90, contact 91, of the reset push button 66, wire 92, contact 86 of the acknowledging relay AR, which was picked up in response to late depression of the acknowledging push button 65, wire 87, contact 71 of the acknowledging push button 65, wire 72, through the winding of the device EPV¹ to common return wire C. The engineer is required to maintain the reset push button 66, which is only accessible from the ground, closed for a time period sufficient to build up pressure in the capacity tank 23 and in sylphon chamber 36 to affect restoration of the pneumatic valve PR. As soon as this valve PR is restored to normal (as shown) pressure is also built up in the sylphon chamber 45 of the air switch AS, thus reclosing the contact 46 and in turn the auxiliary circuit for the device EPV¹ heretofore traced. The engineer may now release the reset push button 66, return to the engine and proceed until he reaches the next wayside signal.

Fig. 3 operation.—For reasons stated in connection with the description of Fig. 2 of the drawings it is deemed unnecessary to specifically describe the modified construction shown in Fig. 3, it being sufficient to describe the operation of this modified construction. Referring to Fig. 3 of the drawings the device EPV¹, which is identical to the one shown in Fig. 2 of the drawings, is normally, that is, under normal clear traffic conditions,

energized through the following circuit:—beginning at the terminal B, wire 26, contact 27 of the control relay CR in its normal energized condition, wires 68 and 94, contact 5 71 of the acknowledging push button 65, wire 95, winding of the device EPV¹, wires 96 and 97, contact 98 of the control relay CR, wire 99 to the common return wire C.

Let us now assume that the train in question enters a caution block in which case, for reasons already given, the control relay CR assumes its de-energized condition, thus causing the circuit for the device EPV¹ just traced to be broken at the contacts 27 and 98 55 of this control relay CR. With the device EPV¹ in its de-energized condition and with valve 18 seated and valve 19 unseated, the whistle W is sounded by reason of the escape of air from the capacity tank or reservoir 23 through the port 24 of the check valve 22.

An appreciable period of time is required to allow the pressure to be materially reduced in this capacity tank 23, this time being sufficient to allow the engineer to re-energize the 20 device EPV¹ in a manner presently to be described.

The engineer if alert will in response to the sounding of the whistle W depress the acknowledging push button 65 and complete 30 the following circuit for picking up acknowledging relay AR before the circuit for EPV¹ (see Fig. 3) is broken at contact 46 of air switch AS:—beginning at the terminal B, wire 74, contact 16 of the control relay CR 35 in its de-energized condition, wires 100 and 101, contact 77 of the acknowledging push button 65, wires 102 and 103, winding of the acknowledging relay AR, to common return wire C. With the acknowledging relay AR 40 energized the following stick circuit is completed:—beginning at the terminal B, wire 74, contact 16 of the control relay CR, wires 100, 101, and 104, stick contact 82 of the acknowledging relay AR, wires 105 and 103, winding of the acknowledging relay AR, to common return wire C. There is still 45 another energizing circuit for the valve EPV¹, namely, the circuit 26, 27, 68, 94, 71 and 95, winding of EPV¹, 96, 108 and 46, 50 but this circuit is of no importance since if contact 27 is closed then contact 98 is also closed and it is immaterial whether or not contact 46 is closed. In other words, the circuit just traced is merely incidental.

55 With this stick circuit completed the engineer may return the acknowledging push button 65 to its normal position, thereby completing the following auxiliary circuit for the device EPV¹:—beginning at the 60 terminal B, wire 106, contact 86 of the acknowledging relay AR, wires 107 and 94, contact 71 of the acknowledging push button 65, wire 95, winding of the device EPV¹, wires 96 and 108, contact 46 of the air switch AS, to common return wire C. With this

auxiliary circuit for the device EPV¹ completed the valves 18 and 19 of this device are restored to their normal position thereby recharging the capacity reservoir 23 before the pneumatic valve PR is operated. The 70 train is thus permitted to proceed through the caution block with the control relay CR in its de-energized condition. When the train reaches the acknowledging loop at the end of the caution block (see Fig. 1) the 75 control relay CR is re-energized, thus breaking the stick circuit for the acknowledging relay AR and restoring the entire car-carried apparatus to its initial normal condition. When the train again passes off of the acknowledging loop the engineer must again perform the acknowledging act, since the next block in advance is presumably occupied and there is no train control current flowing in the track rails.

In the event the engineer is not alert and fails to operate the acknowledging push button 65 within the time required, the reservoir 23 will have been vented to such an extent as to operate the pneumatic relay PR, thereby 80 effecting a brake application and opening the contact 46 of the air switch AS, so that the device EPV¹ can not be manually restored. With the contact 46 once opened, 85 acknowledging by the engineer will be ineffective, for even though the acknowledging relay AR is picked up the auxiliary circuit heretofore traced and including the contact 46 will remain open, and the brakes will remain applied. The train is thus brought to a stop and the engineer must either wait until traffic conditions have cleared up, so as to complete the original circuit for the device EPV¹, or the engineer must alight to 90 the ground and operate the pneumatic reset 95 device comprising the valve 38, operated by a handle 20.

If the engineer alights to the ground and operates the handle 20, which is only accessible from the ground, to the dotted position, main reservoir pressure may flow from such reservoir to the capacity tank 23. After this tank 23 has been fully charged the handle 20 may be returned to its normal position in which event fluid pressure will flow from tank 23 to the sylphon valve 36, thereby restoring the pneumatic relay PR to normal. With this pneumatic relay PR once restored to its normal condition pressure is applied 100 to pipe 44 leading to the brake control apparatus to release the brakes, and to the sylphon chamber 45 of the air switch AS, and since the engineer has presumably already actuated his acknowledging push button 65 and picked up his acknowledging relay 105 AR, the auxiliary circuit heretofore traced and including the contact 86 of relay AR and the contact 46 of the air switch AS is again completed, thus permitting the train 110 to proceed to the next signal in advance.

Applicant has thus described three forms of the invention, comprising a permissive train control system requiring an acknowledging act by the engineer at each caution and each of a plurality of successive danger signals, and has shown by these modified constructions how the acknowledging and reset functions may be accomplished either electrically or pneumatically and has illustrated how the engineer may be penalized for his failure to perform an acknowledging act when he should manifest his vigilance either by pneumatic or electrical apparatus; it is desired to be understood however that these various constructions have been selected to illustrate how the invention may be performed, and it is further desired to be understood that the systems shown and described have not been selected to illustrate the exact construction preferably employed in practicing the invention, but that various changes, modifications, and additions may be made to adapt the invention to local conditions, all without departing from the spirit or scope of the invention or the idea of means underlying the same except as demanded by the scope of the following claims.

What I claim is:—

1. In a continuous inductive train control system of the type wherein the engineer must manifest his vigilance at each caution and stop signal to prevent a brake application, the combination with a car-carried relay responsive to the flow of current in the track rails, an electro-pneumatic valve controlled by said relay and energized when said relay is energized to charge a chamber with fluid pressure and which valve if de-energized vents said chamber through a restricted opening, a pneumatic relay controlled by the pressure in said chamber which in response to such pressure maintains suitable brake applying means inactive whereby the venting of said chamber through said restricted opening causes a delayed brake application in response to de-energization of said main relay, supplemental means for applying fluid pressure to said chamber if the engineer manifests his vigilance, and trackway means for causing the flow of current in the track rails throughout each clear block and for a short distance near the end of each caution and danger block.

2. A continuous inductive train control system of the type wherein the engineer must manifest his vigilance at each caution and stop signal to prevent a brake application, the combination with a car-carried relay responsive to the flow of current in the track rails, an electro-pneumatic valve controlled by said relay and energized when said relay is energized to charge a chamber with fluid pressure and which valve if de-energized vents said chamber through a restricted opening, a pneumatic relay controlled by the

pressure in said chamber which in response to such pressure maintains suitable brake applying means inactive, whereby the venting of said chamber through said restricted opening causes a delayed brake application in response to de-energization of said relay, supplemental means for applying fluid pressure to said chamber if the engineer manifests his vigilance, which means remains active only so long as said main relay remains de-energized, and trackway means for causing the flow of current in the track rails throughout each clear block and for a short distance near the exit end of each caution and danger block.

3. In a continuous inductive train control system of the type wherein the engineer must manifest his vigilance at each caution and stop signal to prevent a brake application, the combination with a car-carried relay responsive to the flow of current in the track rails, an electro-pneumatic valve controlled by said relay and energized when said relay is energized to charge a chamber with fluid pressure, and which valve if de-energized vents said chamber through the pressure in said chamber which in response to such pressure maintains suitable brake applying means inactive whereby the restricted venting of said chamber through said opening causes a delayed brake application in response to de-energization of said main relay, pneumatic means for operating said electro-pneumatic valve pneumatically, acknowledging means which if operated while said main relay is de-energized maintains said pneumatic means active so long as said main relay remains de-energized, and trackway means for causing the flow of train control current in the trackway throughout a clear block and at the exit end of each caution and danger block.

4. In a continuous inductive train control system of the type wherein the engineer must manifest his vigilance at each caution and stop signal, to prevent a brake application, the combination with a car-carried relay responsive to the flow of current in the track rails, an electro-pneumatic valve controlled by said relay and energized when said relay is energized to charge a chamber with fluid pressure, and which valve if de-energized vents said chamber through the restricted opening, a pneumatic relay controlled by the pressure in said chamber which in response to such pressure maintains suitable brake applying means inactive, whereby the restricted venting of said chamber through said opening causes a delayed brake application in response to de-energization of said main relay, pressure operated means for operating said electro-pneumatic valve pneumatically, acknowledging means which if operated while said main relay is de-energized maintains said pressure operated means charged with fluid pressure through

the medium of a stick valve opened by a drop in fluid pressure of said pressure operated means, and trackway means for causing the flow of train control current in the track rails throughout a clear block and at the exit end of each caution and danger block.

5. In a continuous inductive train control system of the type wherein the engineer must manifest his vigilance at each caution and stop signal to prevent a brake application, the combination with a car-carried main relay responsive to the flow of current in the track rails, an electro-pneumatic valve controlled by said relay and energized when said relay is energized to charge a chamber with fluid pressure, and which if de-energized vents said chamber through a restricted opening, a pneumatic relay controlled by the pressure in said chamber which in response to such pressure maintains suitable brake applying means inactive, whereby the restricted venting of said chamber through said opening causes a delayed brake application in response to de-energization of said 25 main relay, pressure operated means for operating said electro-pneumatic valve pneumatically, acknowledging means which if operated while said main relay is de-energized maintains said pressure operated 30 means charged with fluid pressure through the medium of a stick valve which valve is opened by a drop in fluid pressure, means for releasing pressure from said pressure operated means upon re-energization of said 35 main relay, and trackway means for causing the flow of train control current in the track rails throughout a clear block and at the exit end of each caution and danger block.

6. Car-carried apparatus for automatic train control systems comprising, a valve, an electro-magnet for directly mechanically operating said valve, fluid pressure responsive means for directly mechanically operating said valve, brake controlling means controlled by said valve, a relay controlled in accordance with traffic conditions for controlling the continuity of the energizing circuit for said electro-magnet, and manually operable acknowledging means for applying pressure to said pressure responsive means.

7. Car-carried apparatus for automatic train control systems comprising, a valve, an electro-magnet for directly operating said valve, pressure responsive means for directly operating said valve, brake controlling means controlled by said valve, a main relay controlled in accordance with traffic conditions for when energized to energize said electro-magnet, an electro-pneumatic valve energized when said main relay is de-energized to conduct fluid pressure to said pressure responsive means, and a normally open manually operable stick valve connected to said pressure responsive means which stick valve 65 if manually closed is held closed by pressure

applied to said pressure responsive means, whereby upon de-energization of said main relay manual operation of said stick valve is necessary to prevent an application of the brakes.

8. Car-carried apparatus for automatic train control systems comprising, a valve, an electro-magnet for directly operating said valve, pressure responsive means for directly operating said valve, brake controlling means controlled by said valve, a main relay controlled in accordance with traffic conditions for when energized to energize said electro-magnet, an electro-pneumatic valve energized when said main relay is de-energized to conduct fluid pressure to said pressure responsive means, and a normally open manually operable stick valve connected to said pressure responsive means which stick valve if manually closed is held closed by pressure applied to said pressure responsive means, whereby upon de-energization of said main relay manual operation of said stick valve is necessary to prevent an application of the brakes, and reset means accessible only from the ground for restoring said brake control means to normal.

9. Car-carried apparatus for automatic train control systems comprising, fluid pressure operated brake control means, an electro-pneumatic valve which if energized applies pressure to said fluid pressure operated valve, a pressure responsive contact closed only when fluid pressure is applied to said fluid pressure operated means, a circuit for energizing said electro-pneumatic valve closed under favorable traffic conditions ahead and including said contact, means accessible only from the ground for connecting said fluid pressure operated means to a charged reservoir to effect closure of said contact, and manually controllable means for closing an auxiliary circuit through said electro-pneumatic valve and including said contact.

10. Car-carried apparatus for automatic train control systems comprising, fluid pressure operated brake control means, an electro-pneumatic valve which if energized applies pressure to said fluid pressure operated valve through a check valve having a restricted bypass, a pressure responsive contact closed only when fluid pressure is applied to said fluid pressure operated means, a circuit for energizing said electro-pneumatic valve closed under favorable traffic conditions ahead and including said contact, means accessible only from the ground for connecting said fluid pressure operated means to a charged reservoir to effect closure of said contact, and manually controllable means for closing an auxiliary circuit including said contact through said electro-pneumatic valve.

11. Car-carried apparatus for automatic train control systems comprising, fluid pressure operated brake control means, an electro-

- pneumatic valve which if energized applies pressure to said fluid pressure operated valve, a pressure responsive contact closed only when fluid pressure is applied to said fluid pressure operated means, a circuit for energizing said electro-pneumatic valve closed under favorable traffic conditions ahead and including said contact, means accessible only from the ground for connecting said fluid pressure operated means to a charged reservoir to effect closure of said contact, and manually controllable means for closing an auxiliary circuit through said electro-pneumatic valve, said circuit including said contact and a normally closed contact of said manually controllable means, whereby said manually controllable means is protected against misuse, in that it must after operation be returned to normal to permit closure of said auxiliary circuit.
12. Car-carried apparatus for automatic train control systems comprising, a normally charged pipe which if vented effects an automatic brake application, normally energized electro-pneumatic means for maintaining said pipe charged, means controlled from the trackway and effective under clear traffic conditions to maintain said electro-pneumatic means energized, and manually controllable pneumatically operated means effective only under non-clear traffic conditions and then only if the brakes have not yet been automatically applied for maintaining said pipe charged.
13. Car-carried apparatus for automatic train control systems comprising, a normally charged pipe which if vented effects an automatic brake application, normally energized electro-pneumatic means for maintaining said pipe charged means controlled from the trackway and effective under clear traffic conditions to maintain said electro-pneumatic means energized, and manually controllable pneumatically operated means effective only under non-clear traffic conditions and then only if the brakes have not yet been automatically applied for maintaining said pipe charged, and means for protecting said pneumatically operated means against misuse.
50. In testimony whereof I affix my signature.

WADE H. REICHARD.
